REMOVABLE STRAINER FOR RADIATOR CIRCULATING SYSTEMS

Luther C. Wetherell, Hot Springs, Ark.

Application November 1, 1944, Serial No. 561,382

1 Claim. (Cl. 210—169)

This invention relates to strainers, and aims to provide a useful and practical radiator strainer which may be easily installed or removed and which is at the same time adjustable in diameter to accommodate the size of the tube or hose, whereby the circulating water for cooling the motor of an automotive vehicle is strained prior to entering the radiator. Thus the damage resulting from clogging of the circulating water system is eliminated, and the strainer can readily be removed for cleaning as often as desired, generally once every six months.

The strainer may be installed in any desired position in the water system, such as, for instance, in the radiator, in the hose leading from the engine to the radiator intake, in the engine outlet, etc. It may also be installed under the radiator filling cap in order to strain out sediment or trash contained in the filling water.

The above and other objects will become apparent in the following description, wherein characters of reference refer to like-numbered parts in the accompanying drawing. It is to be noted that the drawing is intended to serve the purpose of illustration only, and it is neither desired nor intended to limit the invention necessarily to the specific details of construction shown excepting insofar as they may deemed essential to the invention.

Referring briefly to the drawing,

Fig. 1 is a perspective view of the adjustable strainer.

Fig. 2 is a central longitudinal sectional view through a fragment of a hose or pipe union having the strainer mounted between the members of the union, the strainer being shown in section on the line 2—2 of Fig. 1.

Fig. 3 is a diagrammatical side elevational view of an automobile engine, partly in section and partly broken away, illustrating one manner in which the strainer may be incorporated in the water cooling system thereof.

Referring in detail to the drawing, the numeral 10 indicates a split ring the upper portion 11 of which has an extension 12 reaching approximately to the edge 13 of the split vertically down the upper portion of the ring. The lower portion 14 of the ring 10 likewise has a complementary extension 15 of the same length as the extension 12 and reaching approximately to the edge 16 of the split vertically up the lower portion of the ring. It is apparent that the ring 10 is readily expandable or contractible so as to vary its diameter. Moreover, it is made of resilient material which normally urges the extensions 12 and 15 away from their respective limit stop walls 13 and 16, so that the normal tend-

ency of the ring is to maintain a relatively large diameter.

The upper portion 11 of the ring, including the extension 12, has an overhanging flange 17 externally thereon. A wire mesh screen or the like 18 is formed into the general shape of a cone, and the upper open edge thereof is secured to the lower edge of the ring 10. The screen 18 is split longitudinally and one edge of the split 10 overlaps the other so that the upper diameter of the cone may be readily varied by the two mutually overlapping edges of the screen sliding upon each other in an obvious manner. Within the range of variability of the diameter of the ring 10 the two edges 18 and 20 will thus always overlap so that there will be no open space in the screen regardless of the diameter of the ring.

One example of removably mounting the strainer in a water circulating system is illustrated in Figs. 2 and 3. The motor outlet pipe 22 has joined thereto by a removable coupling 23 the hose 21 leading to the radiator 24. With this coupling removed so as to free the end of the hose from the pipe 22, the strainer is set into the opening in the pipe 22 and seated on the upper edge of the pipe as shown, with the flange 17 resting on the said upper edge of the pipe and the peripheral wall of the ring in contact with the pipe wall. The flexibility of the ring will cause it to expand into the seating position just described. The hose is then attached to the pipe by the union 23. The circulating water flowing into the motor from the radiator will thus obviously be strained and dirt which otherwise would get into the motor will be trapped in the strainer.

The example given of the installation of the strainer in the above paragraph is by way of illustration only, as the strainer may obviously be installed at any point in the system where desired and feasible, and if desired more than one strainer may be used. But no matter in what section of the system it is installed, it is apparent that the ring 10 will expand to provide a snug fit and to cause a complete straining of the flow 45 over the entire cross-sectional area of the pipe or tube.

Obviously, modifications in form and structure may be made without departing from the spirit and scope of the invention.

50 I claim:

An expandable strainer comprising a resilient split ring having a conical screen secured thereto and depending therefrom, said screen having a longitudinal split and having the edges thereof 55 at the split overlapping each other, said ring having an external flange extending from the upper edge thereof.

LUTHER C. WETHERELL.
